UNITED STATES PATENT OFFICE.

SAMUEL GEORGE TATE, OF CHICAGO, ILLINOIS, ASSIGNOR TO UNION SPECIAL MACHINE COMPANY, OF CHICAGO, ILLINOIS, A CORPORATION OF ILLINOIS.

SEAM.

1,353,554.

Specification of Letters Patent. Patented Sept. 21, 1920.

Application filed July 7, 1916. Serial No. 107,959.

To all whom it may concern:

Be it known that I, SAMUEL GEORGE TATE, a citizen of the United States, residing at Chicago, in the county of Cook, State of

5 Illinois, have invented certain new and useful Improvements in Seams, of which the following is a description, reference being had to the accompanying drawing and to the figures of reference marked thereon.

10 The present invention relates to new and useful improvements in seams for sewed articles, and more particularly to a flat seam for uniting the abutted edges of fabric sections.

15 An object of the invention is to provide a seam of the above character which consists of two pairs of needle threads formed into loops and passed through the fabric sections, and wherein the needle loops of re-

20 spective pairs of needle threads are secured by looper threads respectively, one of which looper threads is so concatenated with the needle loops of the corresponding pair of needle threads as to prevent the seam from

25 raveling when a strain is placed on the fabric sections tending to separate their abutted edges.

In the drawings, which show by way of illustration one embodiment of the invention:—

30 Figure 1 is a top plan view on an enlarged scale showing fabric sections united by my improved arrangement of stitching threads;

Fig. 2 is a bottom plan view of the seams;

35 Fig. 3 is a bottom plan view of the fabric sections showing the looper thread which secures two of the rows of needle loops;

Fig. 4 is a view, similar to Fig. 3, but showing the arrangement of the looper threads which unite the other two rows of needle loops.

40 The invention comprises generally a seam for sewed articles consisting of trimmed and abutted edges of knitted fabric which are first united by stitches including two needle threads formed into rows of loops penetrating the respective fabric sections on opposite sides of the meeting edges of fabric sections, a cross thread which connects the

45 needle threads on one face of the fabric, and a looper thread which connects the needle loops on the other face of the fabric, said looper thread being formed into a line of single chain loops disposed entirely on

50 one side of the meeting edges of the fabric

sections. The fabric sections are then united by stitches consisting of two needle threads, each of which is formed into a row of needle loops, said rows of needle loops being disposed respectively on opposite sides 60 of the meeting edges of the fabric sections, a cross thread connecting the needle threads on one face of the fabric, and a looper thread connecting the needle loops on the other face of the fabric, said looper thread 65 being formed into a series of loops respectively concatenated with each pair of the needle loops so that the loop formed in the looper thread of this series of stitches is relatively enlarged, whereby, if released, a 70 strain on the fabric sections will fail to draw the enlarged loop through the needle loop, and whereby said enlarged loop extends across the meeting line of the seam and a strain on the fabric sections will pro- 75 duce opposed strains on the looper thread loop, all of which cooperates to prevent the raveling of the seam when said fabric sections are under strain, as referred to above. The last-named series of stitches are ar- 80 ranged so as to cover the ends of the loops formed in the first-named looper thread, and thus prevent said first-named looper thread from raveling. It will be understood, of course, that these two series of stitches may 85 be made in one on the same machine, one being formed slightly in rear of the other so as to bring about this overlapped relation of the stitches.

Referring more in detail to the drawings:—

The seam consists of two fabric sections 1 and 2, the edges of which are trimmed and abutted, as at 3. In the formation of my seam, these edges are first joined by 95 stitches made by two spaced needles carrying needle threads 4 and 5, respectively. These needle threads are formed into loops 6 and 7 which are passed through the fabric sections on opposite sides respectively of the 100 abutted edges 3. The needle threads are joined on one face of the fabric by a cross thread 8, which passes about each needle loop, as clearly shown in Fig. 1. The needle loops are secured on the other face of the 105 fabric by a looper thread 9. This looper thread is formed into loops 10, each loop being passed through first a needle loop 7 and then a needle loop 6. This looper thread loop 10 is locked by the next formed 110

needle loop 6 on the same side of the abutted edges of the fabric so that in effect the looper thread loops form a row of single chain stitches located entirely on one side of the meeting edges of the fabric sections. The strand 11 of the loop 10 is carried around the next needle loop 7, as clearly shown in Figs. 2 and 3 of the drawings.

The fabric sections are then joined by a series of stitches consisting of two needle threads 12 and 13. These needle threads are formed into a series of loops 14 and 15, respectively, and said needle loops are passed through the fabric sections so that the needle loops 14 are located on one side of the meeting edges of the fabric sections, while the loops 15 are on the other side of the meeting edges of the fabric sections. These needle thread loops 14 and 15 are also disposed on opposite sides of the single chain stitches in the looper thread 9, referred to above. On one face of the fabric, the needle threads 14 and 15 are joined by a cross thread 16, which is laid about each needle loop, as clearly shown in Fig. 1 of the drawings. This cross thread is laid on the same face of the fabric as the cross thread 8. On the other face of the fabric the needle loops 14 and 15 are locked by a looper thread 17 which is formed into loops 18, and each loop is passed first through a needle loop 15 and a needle loop 14, and this looper thread loop 18 extends about and is locked by the next two formed needle loops 14 and 15. As a result the loop 18 from a point where it emerges from the needle loop 14 is considerably enlarged and extends across the meeting edges of the fabric sections. The looper thread loop 18 covers and ties down the single chain stitches formed in the looper thread 9, and thus prevents the loops in the looper thread 9 from raveling.

It has been found in practice that the stitches having the loops formed as a single row of chain stitches on one side of the meeting edges only may ravel when a strain is placed on the fabric sections tending to separate the same. The loop projecting beyond the needle thread loop is relatively small and may be pulled out by this strain so that the threads will ravel. The second series of stitches either in part or in whole overlaps the first-named stitches. In the drawings, I have shown these second series of stitches partly overlapping the first-named series of stitches. This overlapping of one of the first-named series of stitches prevents raveling, as the threads of the overlapping stitches tie down and hold the ends of the loops formed in the looper thread of the first-named stitches. Furthermore, this second series of stitches will not ravel for the reason that the looper thread loop, as above noted, is very much enlarged beyond the

point where it passes through the last needle thread, and even if the loop itself is released through a raveling out of the loops which lock the same, a strain on the fabric will fail to pull said enlarged loop through the needle loop before the needle loop is drawn small enough to tie closely about the looper thread loop and thus hold the same. Furthermore, any strain on the fabric sections which would tend to separate these fabric sections at their abutted edges would pull in opposite directions on these looper thread loops, for the reason that each loop extends across the meeting edges of the fabric sections and is locked by two needle loops passing therethrough, which needle loops are disposed on opposite sides of the meeting sections.

From the above, it will be apparent that this second-named series of stitches coöperating with the first-named series of stitches forms an effective covering seam for the meeting edges of the abutted sections of fabric, wherein the series are slightly overlapped and wherein all the stitches pass through the fabric adjacent the meeting edges and serve to tie down and cover any loose ends of threads of the fabric and other stitches pass through the fabric sections well back from the meeting edges, thus forming a firm anchorage for the stitches. The second-named series of stitches covers in part the first-named series and prevents the same from raveling, as above noted, and the second-named series is of itself constructed so as not to ravel.

While I have shown this second series of stitches with enlarged looper thread loops as covering in part a stitch of a different character, it is obvious that minor changes in the character of the stitches used and the arrangement of the threads may be made without departing from the spirit of the invention, which consists primarily in the use of this two needle series of stitches having the looper thread with the enlarged loop which overlaps and prevents the raveling of the ends of the loops of another series of stitches which are used in joining the fabric sections. In the formation of a seam, the overlapping sections of fabric are fed in the direction indicated by the arrow in the Figs. 2, 3 and 4.

Having thus described the invention, what I claim as new and desire to secure by Letters-Patent is:—

1. A seam for sewed articles comprising fabric sections having their edges abutted, a series of stitches connecting said sections and comprising spaced rows of opposed needle thread loops respectively extending through the fabric sections on opposite sides of the abutted edges, a looper thread concatenated with said needle thread loops and forming a line of single chain loops on one

side of the meeting edges of the fabric sections, and a separate series of stitches connecting and anchoring said fabric sections against being separated by a strain transverse of the meeting edges of the fabric sections, said separate series of stitches including spaced rows of opposed needle thread loops and a looper thread concatenated therewith, said last-mentioned looper thread being formed into a series of loops respectively concatenated with each pair of the last-mentioned needle thread loops after passing through the needle thread loops of a previous pair and extending over and covering the chain loops of the first-mentioned looper thread.

2. A seam for sewed articles comprising fabric sections, and a series of stitches connecting the adjacent edges thereof, said stitches comprising two needle threads formed into rows of needle loops penetrating the fabric sections respectively on opposite sides of the adjacent edges, a looper thread formed into a series of loops, each looper thread loop being concatenated with opposed needle thread loops, a cross thread

disposed on the opposite face of the fabric and connecting the needle threads, a separate series of stitches connecting and anchoring said fabric sections against being separated by a strain transverse to the adjacent edges of the fabric sections, said second series of stitches including needle threads formed into a series of loops penetrating the fabric sections on opposite sides of the adjacent edges, a cross thread connecting the needle threads on the same side of the fabric sections as the first-named cross thread, and a looper thread formed into a series of loops each passing around opposed needle thread loops in said second series of stitches after passing through the needle thread loops of a previous pair in said second series of stitches and extending over and covering the ends of the loops formed in the first-named looper thread.

In testimony whereof, I affix my signature in the presence of two witnesses.

SAMUEL GEORGE TATE.
